Primary Examiner — Eric Goodman*Assistant Examiner* — John R Yeh(74) *Attorney, Agent, or Firm* — Cantor Colburn LLP(57) **CLAIM**

We claim the ornamental design for a washing machine, as shown and described.

DESCRIPTION

FIG. 1 is a perspective view of a washing machine, showing our new design in an exemplary embodiment;

FIG. 2 is a front elevation view thereof;

FIG. 3 is a rear elevation view thereof;

FIG. 4 is a side elevation view thereof;

FIG. 5 is a another side elevation view thereof;

FIG. 6 is a top plan view thereof; and,

FIG. 7 is a bottom plan view thereof.

The broken lines illustrating portions of the washing machine are for environmental purposes only and form no part of the claimed design.

1 Claim, 6 Drawing Sheets(56)
